(57) **CLAIM**

The ornamental design for a human machine interface for outdoor power equipment, as shown and described.

DESCRIPTION

FIG. 1 is a perspective front view of a human machine interface for outdoor power equipment in accordance with an embodiment of the present invention;

FIG. 2 is a side perspective view of the human machine interface for outdoor power equipment of FIG. 1;

FIG. 3 is a top view of the human machine interface for outdoor power equipment of FIG. 1;

FIG. 4 is a left side view of the human machine interface for outdoor power equipment of FIG. 1;

FIG. 5 is a right side view of the human machine interface for outdoor power equipment of FIG. 1;

FIG. 6 is a front side view of the human machine interface for outdoor power equipment of FIG. 1;

FIG. 7 is a rear side view of the human machine interface for outdoor power equipment of FIG. 1;

FIG. 8 is a perspective view of the human machine interface for outdoor power equipment of FIG. 1 disposed on the handle of a piece of outdoor power equipment; and,

FIG. 9 is a perspective view of the human machine interface for outdoor power equipment of FIG. 1 disposed on the handle of a different piece of outdoor power equipment.

The broken showing of outdoor power equipment in FIGS. 8 and 9 show environments of use. The remaining broken lines shown in the drawings depict portions of the human machine interface for outdoor power equipment. The broken lines form no part of the claimed design.

1 Claim, 6 Drawing Sheets
